UNITED STATES PATENT OFFICE.

EDWARD L. MORRIS, OF BOSTON, MASSACHUSETTS.

DESIGN FOR A TOY.

SPECIFICATION forming part of Design No. 14,835, dated February 26, 1884.

Application filed August 8, 1883. Term of patent 3½ years.

To all whom it may concern.

Be it known that I, E. L. MORRIS, a citizen of the United States, residing at Boston, in the county of Suffolk and State of Massachusetts, have invented a new and original Design for a Toy, of which the following is a specification.

My design relates to an improved toy; and it consists of peculiar features, as hereinafter set forth.

In the accompanying drawing my design is illustrated.

A is a toy vehicle formed to represent a flat-

boat or scow. A loose-jointed rider, B, is seated in the boat, and represents an oarsman. The general appearance of the toy is intended to be uncouth and amusing, as though a water-craft had been adapted to propulsion on land.

I claim—

The design for a toy, as shown and described.

EDWARD L. MORRIS.
